UNITED STATES PATENT OFFICE.

DANIEL I. REITER, OF NEW YORK, N. Y.

KEY-CASE HOLDER.

1,403,445.

Specification of Letters Patent. Patented Jan. 10, 1922.

Application filed February 11, 1921. Serial No. 444,148.

To all whom it may concern:

Be it known that I, DANIEL I. REITER, a citizen of the United States, and a resident of the city of New York, borough of Manhattan, in the county and State of New York, have invented a new and Improved Key-Case Holder, of which the following is a full, clear, and exact description.

This invention relates to a new and improved key case holder, and has for an object a holder which can be made and stamped of sheet metal and bent and formed into shape ready for the application of key latches thereto in a simple and economical manner.

Another object resides in the particular construction and arrangement of parts hereinafter described and claimed and shown in the accompanying drawings.

20 The invention is illustrated in the drawings, of which—

Figure 1 is an elevation of the device;

Figure 2 is a horizontal section taken on the line 2—2 of Figure 1;

25 Figure 3 is a vertical section taken on the line 3—3 of Figure 1;

Figure 4 is an elevation of a modified form of holder; and

30 Figure 5 is a vertical section taken on the line 5—5 of Figure 4.

As shown in the drawings, the invention is embodied in a preferred form which is attached to a leather fold case 1. The invention comprises a body portion of sheet metal 2 which may be suitably connected, as by rivets 3, to the leather fold or case 1.

35 The leather case is provided with overlapping fold portions 4 and 5 to which are connected suitable fastening means, such as 6, whereby the sheet metal to which the keys are attached, in a manner hereinafter described, is hidden from view by the overlapping folds 4 and 5 when the keys are not in use. This metal plate 2 along its upper edge, as shown in Figure 1, is stamped out to form a plurality of spaced extending finger portions, the outer ends of which are turned over on the main body portion to form spacing lugs, such as 7, the purpose of

45 which is to be hereinafter described. The space or interval between each lug 7 is in the form of a slot 8 the inner end of which is bridged by a link or strap 9 a short distance from the end 10 of the slot 8. Each

50 of these straps 9, as shown in Figure 2 par-

ticularly, is struck up from the level of the main plate 2 and provides a support adapted to receive key rings or links 11 which may be snapped over the links or straps 9 and engage the same, as shown in Figure 1. The main body portion of the key holders or links 11 will depend from the straps 9 and lie along the body portion of the plate 2, as shown in Figure 1. The lug 7 will tend to keep the key links disposed separate from each other. When the key is to be used, it, with its supporting link 11, is moved around the pivoted strap 9 until the link 11 extends outwardly from the body portion to the plate, separate from the other keys which may be supported on the other links.

In Figures 4 and 5, I illustrate a modified form of the invention in which a sheet-metal plate having a body portion 2' mounted on a flexible leather casing, such as 1', a plurality of apertures, such as 3', are pierced in the plate along and slightly spaced from its upper edge. The upper edge of the plate is turned back in a smooth curve to a point adjacent the body portion, as shown in Figure 5, whereby the apertures 3' are presented in position facing inward at right angles from the body portion 2', and a link, such as 11' shown in dotted lines in Figure 5, can be passed through the aperture and beneath the body portion 2' and the inner edge of the body portion. This modified form eliminates the necessity for providing straps such as the straps 9 previously mentioned. It is slightly less expensive to make than the previous one.

It will be seen, therefore, that by this invention I have provided a simple, economically manufactured article of sheet metal which can, with a minimum number of manufacturing steps be made into a compact efficient article for the purpose of supporting keys. The entire article is made from one single piece of sheet metal which can be stamped out without the necessity for using more than the one element. Such extra attachments as pins, keys or other similar devices are unnecessary to hold the key links in position on the plate.

What I claim is:

1. A key case holder comprising a single sheet of stamped metal adapted to be attached to a flexible folder, a plurality of spaced fingers disposed along one edge of the sheet, the ends of said fingers turned

105

110

back on themselves to form spacing lugs, and straps of metal integral with the sheet disposed across between the lugs to support key holders.

- 5 2. A key case holder comprising a sheet of stamped metal, a plurality of spaced fingers formed along one edge of said sheet, the ends of said fingers being turned back on themselves to form spacing shoulders or 10 lugs, the fingers between their remaining portions and the body portion of the sheet

forming slots, and a plurality of straps formed of metal integral with the sheet disposed across the slots and providing supports for key holders.

15

3. A key case holder comprising a sheet-metal plate having spaced slots therein adjacent one edge of the sheet, and a plurality of straps disposed across the slots to support key holders.

DANIEL I. REITER.
